CLAIM

I claim the ornamental design for an offering envelope box, as shown and described.

DESCRIPTION

FIG. 1 is a top, front perspective view of an offering envelope box showing my new design;

FIG. 2 is a bottom, rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a side elevational view thereof; and,

FIG. 8 is a side elevational view thereof, opposite FIG. 7. The broken lines shown in the drawing disclosure are for illustrative purposes only and form no part of the claimed design.
